CARRIER FOR PNEUMATIC DISPATCH TUBES

Clinton A. Burrows, Glendale, Calif., assignor to
Store Equipment Corporation, a corporation of
California

Application August 27, 1934, Serial No. 741,585

14 Claims. (Cl. 243—34)

This invention relates to carriers of the type used in pneumatic dispatch systems.

At the present time, cylindrical type carriers including a casing or casings are adapted to receive messages, currency, and various data, and which carrier or carriers are thereafter placed within a tube and delivered elsewhere under pneumatic pressure.

In the majority of cases, so far as the inventor is aware, it is impossible to ascertain by merely glancing at the carrier and without opening the same, the destination, the content or contents of the carrier. The pneumatic system utilizing carriers, is possibly more efficient than any other system for determining the credit of a customer, making rapid change or currency, keeping track of sales slips, and the like. However, the dispatch system is open to certain objections, in that the average carrier is so constituted that the content of the carrier cannot be readily ascertained at the receiving station for said carrier where the distributing clerks are situated.

By way of specific example, if it is desired to ascertain the credit standing of a customer desiring to charge an article, a slip with the customer's name may be made out and inserted in the carrier, and after passage through the tube to the receiving station, the receiving station must forward the carrier to the authorizing clerk. Thus, the carrier must be opened by the receiving clerk to determine the proper destination for said carrier, whereupon the carrier must be again opened at its destination prior to returning the carrier. However, to open the carrier, remove the slip, replace the slip, and return the carrier entails delay. This delay becomes more noticeable if the credit asked for is not legitimate, for the reason that the person desiring the credit may become nervous and leave. As a consequence, if the entire operation can be performed within a few seconds of time, in the case of fraud, the house detective can examine the signature before the slip is removed from the carrier and readily apprehend the culprit prior to leaving the designated spot. For instance, the article purchased may be in the process of wrapping during the time that the carrier is in transit.

An object of the present invention is the provision in a carrier of means whereby any slip bearing notations can be readily read without opening the carrier.

The inventor is aware that carriers have heretofore been suggested, wherein the said carrier embodies some transparent member adapted to

permit observation of the contents of the carrier. However, so far as the inventor is aware, carriers of this type are not used, due to the fact that said carriers are open to many objections from a structural standpoint.

By way of example, it may be stated that carriers that the inventor is familiar with are not fool proof in operation, are structurally weak, subject to damage, shortlived, do not always function in the manner intended, are expensive in cost of manufacture, and with parts of the carrier liable to separate and spill the contents.

My invention overcomes the deficiencies above enumerated and provides a carrier having a transparent inner cylinder adapted to resist stress, a carrier embodying means whereby the contents of the carrier may be observed, which said means is so arranged and constructed as to not be subjected to any stress during movement of the carrier through a pneumatic tube, or to be subjected to any stress other than that of torque when the carrier is opened.

Other objects of the invention, including inexpensiveness in cost of manufacture and general superiority over existing carriers now known to the inventor, and ease of assemblage, will be detailed as the specification proceeds, and with the above and other objects in view, the invention consists in the novel and useful provision, formation, construction, association, and interrelation of parts, members and features, all as shown in certain embodiments in the accompanying drawings, described generally, and more particularly pointed out in the claims.

In the drawings:

Figure 1 is a plan view of the improved carrier shown within a pneumatic tube, said tube being fragmentary and in longitudinal section,

Figure 2 is a side elevation of the inner shell member of the invention,

Figure 3 is an end elevation of the shell member shown in Figure 2, looking in the direction of the arrow of said figure,

Figure 4 is an elevation of a disk member used in practicing the invention,

Figure 5 is a bottom plan view of the disk of Figure 4,

Figure 6 is a side elevation of the disk of Figure 4,

Figure 7 is a plan view of a ring member of the invention,

Figure 8 is a top plan view of the ring member shown in Figure 7,

Figure 9 is a plan view of a disk adapted to

cooperate with the disk and ring of Figures 4 and 7.

Figure 10 is a sectional view on the line 10—10 of Figure 9.

5 Figure 11 is a longitudinal sectional view on an enlarged scale of the invention, the said view being taken on the line 11—11 of Figure 1.

Figure 12 is a cross sectional view on the line 12—12 of Figure 11, and,

10 Figure 13 is a sectional view on the line 13—13 of Figure 11.

Referring now with particularity to the drawings, I have shown at 1 the improved carrier within a tube 2. As is customary in systems of 15 the character of this invention, the said carrier is placed within a tube and moves therethrough under pneumatic pressure. Accordingly, stations are established at different zones, for instance, adjacent a counter, with said tube terminating 20 at what is known as a distribution zone, the clerks at said zone in turn redistributing the said carriers through suitable tubes to the authorizing clerks. The system is much the same as a telephone system wherein a main office receives 25 the call and in turn connects with the proper party. To this end, as has previously been pointed out, it becomes important for reasons that will readily suggest themselves to those skilled in the art, to save time and needless effort and 30 motions on the part of the distribution clerks. Return tubes are likewise provided so that, after the subject matter of the contents of the carrier has been examined, an immediate return may be made to the initial point. Within the 35 purview of my invention, I have provided a carrier having an inner shell in part constructed of transparent material so that the contents of said carrier may at all times be readily observed. As these carriers move with considerable speed with- 40 in the pneumatic tubes, it is essential that when the carrier drops within a receiving basket from the tube, that the fragile inner shell be not injured. It will be appreciated that if the carrier contains currency in addition to a suitable 45 sales slip, the carrier in dropping within a receiving basket will strike the basket with considerable force, and with my invention, I have the parts so constructed that the inner shell is relieved of this stress.

50 In its simplest embodiment, my improved carrier comprises outer and inner shell members, the inner shell being closely nested within the outer shell and turnable relative to the outer shell. The inner shell is preferably formed of some 55 transparent material, such as celluloid. The carrier is provided with conventional bumper members at both ends. One of said bumper members is secured to the outer shell and the other of said bumper members is secured to suitable end mem- 60 bers embodying locking mechanism, directly as- 65 sociated with but not attached to the inner and outer shells. The relationship of these end mem- 70 bers with the two shells is such that the inner shell "floats", that is to say, the inner shell is allowed slight longitudinal movement within the outer shell and does not have a rigid connection with the locking mechanism nor with the bumper members or heads. Thus, it is possible for me to construct all of the inner shell of transparent 75 material using a very small portion of metal at the ends,—just sufficient to make the shell retain its cylindrical form. This transparent material will not withstand great shock but my construc- 80 tion relieves it of such shock. These locking

members are so constructed and arranged that the only stress subjected to the transparent inner shell is due to torque. This transparent inner shell is provided with a conventional opening in the side adapted to register with a corresponding opening in the outer shell, when the parts are moved to cause such registration. The inner shell may be rotated relative to the outer shell, to the end that a portion of the transparent shell may entirely cover the segmental 10 opening of the outer shell, and when so positioned, to lock against further movement.

5 I also incorporate in my present invention suitable means for limiting the rotative movement of the inner shell relative to the outer shell 15 in two directions. Also incorporated within the inner shell is suitable means whereby a slip bearing indicia will be so held within the inner shell that as the inner shell is turned, the slip moves therewith and the indicia may be viewed 20 through the segmental slot of the outer shell.

Another feature of the invention resides in the 25 means whereby the inner shell, comprising a transparent member, may be suitably held at its terminal portions to the end that distortion, un- 30 der internal stress, and damage is effectively prevented.

Referring to Figure 11, the said carrier includes an outer shell or casing 3 which, in the present instance, is cylindrical in cross section, 30 and an inner cylindrical shell 4 fitted within the outer shell. The relationship and the fit between said shells is such that they may be relatively rotated or turned. The outer shell 3 is preferably formed of some stress-resisting material, 35 such as metal. One end of said shell, as shown at 5, is provided with an inwardly directed annular flange 6. Received within the confines of the shell 3 and bearing against the said flange 6 is a circular plate 7. A bumper head or terminal 40 8, formed of some cushioning material, such as felt, is secured to the said plate 7. This plate is provided with a pair of spaced openings 45 adapted to accommodate the heads 9 of screws 10, the said screws being passed through openings 11 and 12 of the head 8 and threaded in threaded openings 13 of a retaining plate 14 confined within a circular recess 15 extended inwardly from the outer surface of the said head 8.

The head 8 is adapted to overlap the annular 50 flange 6, as shown at 16, and the diameter of said head, in the present instance, is greater than the external diameter of the shell 3.

The said shell 3 is provided with a segmental 55 cut-out portion or opening 17 substantially intermediate its ends, and the cut-out portion is of sufficient area to readily permit access to the interior of the said shell.

The opposite terminal portion 18 of the shell 3 is provided with an annular peripheral rib 19, 60 this rib thereby providing an annular groove 20 on the inner surface of said shell.

The inner shell 4, in the present instance, is 65 formed of transparent material, such as transparent celluloid, and which transparent material is cylindrical in form. This transparent material is provided with a segmental slot 21, the shape and area thereof corresponding to the shape and area of the opening 17 of the outer shell 3. For the purpose of maintaining a cylindrical form, of assuring non-breakage of the transparent material and likewise to reinforce the same against stress, I have provided members designated generally as 22 and 23, respectively for ends of said material. The member 22 is 70 75

formed by two cup-like members 26 and 27, with flanges 28 and 29 slightly spaced to receive under pressure the end portion of said transparent material. The member 23 is formed by two ring members 30 and 31, slightly spaced to receive under pressure between them the opposite end portion of said transparent material. It is intended that the said rings shall closely embrace the said shell 4. It is evident that the cylindrical form of the inner container or shell is thus maintained by the end members 22 and 23, and further, that torque exerted upon one or the other of said members to produce rotation of the inner shell 4 will not distort, to any appreciable extent, the said shell.

Referring to Figures 2 and 3, it will be noted that the inner shell, including the rings 30 and 31, are provided with diametrically disposed notches 32 and 33. Adapted to be received in part within the confines of the inner ring 31 is a disk 34. This disk constitutes an end wall for the inner shell 4, whereby currency or other articles received within the inner shell may be confined between said disk and the base 26, the base 26 constituting the opposite end wall for said shell. This disk 34 is retained in a fixed relation to the end of the outer shell and is provided with radial lugs 35 and 36 fitting in corresponding notches 32 and 33 cut in the end of the inner shell 31, which cause the said inner shell to rotate when the bumper is rotated. The inner shell has sufficient clearance between this disk and the closed end of the outer shell to allow it to move freely, and this clearance also allows free, limited, longitudinal, "floating" motion of said inner shell in relation to the outer shell and with disk 34, thereby preventing any possible longitudinal stress upon the inner shell. The inner face of the disk 34 is provided with a concavity 37 and extending upwardly from the face of said concavity are ribs 38 and 39. The opposite face 40 of said disk is provided with a concentric boss or enlargement 41 and the said face 40 likewise has extending outwardly substantially at right angles thereto a stud 42. The body of the disk, together with the hub, is provided with one or more screw-threaded bores 43 and 44. A plate 45 (see Figures 9 and 10) is provided with a pair of spaced bores 46 and 47 adapted to register with the screw-threaded bores 43 and 44 of the disk 34, and when said plate 45 rests against the face 41 of the boss, the said bores 46 and 47 registering with the bores 43 and 44, the stud 42 passes through an opening 48 provided therefor in the plate 45.

Adapted to be interpositioned between the outer face 40 of the disk 34 and the plate 45 is the means illustrated in Figures 7 and 8. This means functions in several capacities, to-wit: it holds the inner shell confined within the outer shell, it, in conjunction with other members, limits the rotation of the inner shell relative to the outer shell and likewise functions as one member of the locking means for maintaining the inner shell closed to the outer shell, when the elongated slot 47 of the outer shell is covered by the transparent body of the inner shell. The means constitutes a flat, split annulus or ring 49, one portion of the periphery 50 of which is cut-away and reduced as to diameter. The portion 50 forms the terminus for a portion of the annulus adjacent the split 51, and the portion 50 is so bent as to lie out of the horizontal plane of the body of the annulus, as best shown in Figure 8. This portion 50 is formed of spring-

like material. The said annulus has concentric inner edges 52 and 53, and likewise an eccentric inner edge 54. This construction provides abutments, shoulders or stops 55 and 56 between the eccentric and concentric portions. The annulus is provided with a lug 57 extending radially from the periphery thereof.

In the assemblage of the device, the disk 34 is fitted within the ring 31 of the inner shell 4 in such a manner that the lugs 35 and 36 are positioned within the notches 32 and 33. The means 49 is then fitted within the annular groove 20 of the circumferential rib 19. The said means 49 is correctly positioned within the annular groove when the lug 57 is passed through a slot 58 in the said rib (see Figure 11). The fit between the means 49 within the annular groove of the rib is quite tight and if desired, the rib may be crimped so as to positively assure that the said means 49 is not displaced therefrom. Obviously the lug 57, if passed through the slot 58, would prevent turning movement between the said means 49 and the outer shell. In actual practice, it has not been found necessary to crimp the rib as the pressed fit engagement between the said means 49 and the rib is sufficient. Thereafter, the disk or plate 45 is so positioned that the stud 42 is passed through the opening 48. A bumper head 59 of the same construction as the bumper head 8 is provided with a concentric recess 60, within which recess is confined a plate 61 provided with a pair of openings 62 and 63, through which openings and openings in the bumper head are passed screws 64, which screws pass through the openings 46 and 47 of the plate or disk 45 and are threaded within the threaded openings 43 and 44 of the disk 34. Thus, the bumper head, plate 45 and disk 34 are held in working relationship, the means 49 being interposed between the said disk 34 and the said plate 45, as before stated. The boss 41 acts to properly space the plate 45, with the result that the annular space between the said disk 34 and said plate 45 is slightly greater as to transverse dimension than the thickness of the means 49, with the consequence that end play is allowed.

From the description so far given, it is evident that the means 49 acts to restrict end play of the disk 34 in an outward axial direction and that said plate 45 is contact with the open end of the outer shell restricts end play of the plate 34 in an inward axial direction. During any movement in an axial direction of the disk 34 and the plate 45, to which it is connected, it is evident that said end play is not communicated to the inner shell for the reason that the lugs 35 and 36 are free to move within the notches 32 and 33.

The plate 45 is provided on one surface thereof with a projection 65, which may be formed by striking the metal inwardly from one surface, as for instance illustrated in Figure 10. This projection acts as one member of a lock, the other member constituting the part 50, together with the split or notch 51 in the means 49.

Referring to Figure 13, when the inner shell is rotated to a given position, the projection 65 will slide over the face of the part 50 of the means 49, and into the notch or split portion 51. When this occurs, a clicking sound will be audible and the inner shell will be locked closed over the segmental slot 47 of the outer shell 3. The part 50 is downwardly curved at 66, to the end that the projection 65 can force the part 50

50 downwardly to release the frictional lock when the inner shell is turned in the opposite direction through the medium of the bumper head 59 to cause registration between the segmental slots of the outer and inner shells.

When the projection is in part received within the notch or split portion 51, as illustrated in Figure 13, the stud 42 on the disk 34 will abut against the stop 55 of the means 49, thus limiting 10 the rotative movement of the inner shell relative to the outer shell, the transparent body of the inner shell covering or closing the elongated slot 17 of the outer shell. When the inner shell is rotated in an opposite direction, the stud will engage the stop 56 when the elongated slots 17 and 21 of the outer and inner shells register.

The operation, uses and advantages of the invention just described are as follows:

It is apparent from an inspection of the drawings and the description as just given that while a certain amount of end play between the means 49 interposed between the disk 34 and the plate 45 is permitted, that this end play can be controlled to a certain extent. For instance, it will be noted that a surface of the plate 45 abuts against the inturned edge of the annular rib of bead 19 and that by reducing the thickness of the boss 41, the annular space between the disk and plate can be reduced as to cross sectional area.

When it is desired to use the device, some suitable indicia may be mounted upon, painted, or otherwise applied to the carrier, to the end that the station from which the carrier is sent may be 35 readily ascertained by the classification and distribution clerks. If a slip is placed within the carrier and adjacent the disk 34 in such a manner that an edge of the slip is received between the ribs 38 and 39, the slip will be held in position within the inner shell so that it will not 40 slip relative to said shell as the shell is rotated. Thus, the slip may be correctly positioned, to the end that any notations appearing thereon will be 45 visible when the transparent inner shell covers the slot 17 of the outer shell. This notation may be readily read by those in authority and the classification clerk may by glancing through the transparent inner shell, dispatch said carrier to its proper station, without opening said carrier.

50 The outer shell 3 is preferably formed of metal to give strength to the device and, as a consequence, is opaque, although within the purview of my invention, it would be possible to construct the outer shell similarly to the construction of 55 the inner shell so that the outer shell might likewise be transparent in nature.

It is obvious that various changes and modifications and variations may be made in practicing the invention in departure from the particular showing thereof and the description as given without, however, departing from the true scope of the invention as defined by the appended claims.

I claim:

- 65 1. A carrier for pneumatic dispatch tubes, comprising an outer shell, a substantially transparent inner shell, and means for maintaining the inner shell against longitudinal stress within the outer shell.
- 70 2. A carrier for pneumatic dispatch tubes, comprising an inner and an outer shell, bumper heads for ends of said shells; and means whereby the bumper heads are fixed against lateral movement and longitudinal movement of the inner shell is permitted relative to the bumper heads.

3. In carrier construction for pneumatic dispatch tubes; a transparent shell, end members therefor, and a splined connection between one of said end members and the shell.

4. A carrier for pneumatic dispatch tubes, comprising an inner and an outer shell, an end member splined to said inner shell, a ring carried by the outer shell for limiting movement of the inner shell and its splined end in one direction, and means external the said ring and secured 10 to the splined end member for producing relative rotation between the inner and the outer shells.

5. A carrier for pneumatic dispatch tubes, comprising an inner and an outer shell, an end 15 member splined to said inner shell, a ring carried by the outer shell for limiting movement of the inner shell and its splined end in one direction, and means external the said ring and secured 20 to the splined end member for producing relative rotation between the inner and the outer shells, said means and said ring provided with members adapted to detachably interlock when said inner shell is rotated to a definite position relative to the outer shell.

6. A carrier for pneumatic dispatch tubes, comprising an inner shell provided with an end wall and an outer shell, said outer shell provided at one end with a ring adapted to prevent outward movement of the inner shell from the outer shell 30 in one direction, and means on said ring cooperating with means attached to the end wall of the inner shell to limit rotation of said inner shell in two directions.

7. A carrier for pneumatic dispatch tubes, comprising an inner shell provided with an end wall and an outer shell, said outer shell provided at one end with a ring adapted to prevent outward movement of the inner shell from the outer shell in one direction, means on said ring cooperating 40 with means attached to the end wall of the inner shell to limit rotation of said inner shell in two directions, and means for locking said inner shell at the end of its limit of rotation in one direction.

8. A carrier for pneumatic dispatch tubes, comprising an inner and an outer shell, said inner shell provided with end members and one of said end members formed with a spaced pair of ribs adapted to engage a slip or the like placed within 50 said shell to prevent a shift of position of said slip relative to the shell.

9. A carrier for pneumatic dispatch tubes, comprising an inner transparent shell and an outer opaque shell, a pair of spaced apart concentric rings between which ends of said transparent shell are received and secured, a plate forming a continuation of one of said rings to close one end of said transparent shell, a disk for the opposite end of said transparent shell, said 60 disk having a splined connection with the concentric rings and said shell, whereby said shell may shift longitudinally relative to the disk, there being no lateral movement.

10. A carrier for pneumatic dispatch tubes, 65 comprising an inner transparent shell and an outer opaque shell, both shells provided with elongated slots adapted to register when the shells are relatively rotated to one position and to be out of registry when the shells are rotated to a 70 second position, said outer shell being provided at one end with an annular rib, an end member splined to said inner shell, a disk secured to said end member and annularly spaced in part therefrom, and a ring fitted within the rib of said 75

outer shell and received in the annular space aforesaid, said disk and said ring being provided with cooperating locking means to lock the inner shell in a given position when the elongated slots of said inner and said outer shells are out of registry.

11. A carrier for pneumatic dispatch tubes, comprising an inner transparent shell and an outer opaque shell, both shells provided with elongated slots adapted to register when the shells are relatively rotated to one position and to be out of registry when the shells are rotated to a second position, said outer shell being provided at one end with an annular rib, an end member splined to said inner shell, a disk secured to said end member and annularly spaced in part therefrom, a ring fitted within the rib of said outer shell and received in the annular space aforesaid, said disk and said ring being provided with cooperating locking means to lock the inner shell in a given position when the elongated slots of said inner and said outer shells are out of registry, and said ring being formed with stops to limit the rotation of said inner shell relative to the outer shell in two directions.

12. The combination in a pneumatic dispatch carrier having an outer shell and an inner trans-

parent shell, of means for closing one end of said inner shell, said means and said inner shell being so related as to permit limited movement of said inner shell relative to said means to provide a floating inner shell within the outer shell.

5

13. The combination in a carrier for pneumatic dispatch systems, of an outer opaque shell and an inner transparent shell, both formed with the usual side openings adapted to register when the shells are rotated to one position and to be out of registry when the shells are rotated to a second position, said inner shell provided with an end, and means on said end adapted to engage a slip or the like whereby said slip remains in a determined position within the inner shell during relative rotation between the said shells, the said slip being visible through the said transparent shell.

10

14. The combination in a pneumatic dispatch carrier having an outer shell and an inner transparent shell, means for closing one end of said shell, said means and said inner shell being maintained in splined relationship to permit limited longitudinal movement of said inner shell relative to said means to provide a floating inner shell within the outer shell.
